UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FILLING-CATCHER FOR LOOMS.

1,383,874.

Specification of Letters Patent. Patented July 5, 1921.

Application filed May 27, 1920. Serial No. 384,611.

To all whom it may concern:

Be it known that I, MELVIN L. STONE, a citizen of the United States, residing at Lawrence, in the county of Essex and State 5 of Massachusetts, have invented an Improvement in Filling-Catchers for Looms, of which the following description, in connection with the accompanying drawings, is a specification, like characters on the drawings representing like parts.

This invention relates to filling replenishing looms, and more particularly to a filling or thread catcher for removing the old filling from the loom when the filling has been 15 replenished.

In looms of this general type, when the filling in the shuttle is replenished, the piece of old filling or that extending from the substantially-exhausted filling carrier is caught 20 or parted between the cloth selvage and the shuttle-box, and the two ends of the parted filling are moved frontwardly of the loom. At such time the frontward movement of the clamp which holds the ends of the filling, 25 will draw the filling from the shuttle-box either entirely or partly, and will stretch the filling end leading from the cloth selvage diagonally toward the front of the loom.

One of the important features of the present invention is to dispose of the piece of filling which extends between the thread 30 parter and clamp to the cloth selvage after a replenishing operation, and the action of the thread parter and clamp. This feature 35 of the invention is carried into effect by a yielding thread catcher which, when the thread parter and clamp have performed their parting and clamping functions and have been moved frontwardly, rests upon the 40 piece of filling extending between the thread parter and clamp and the cloth selvage, and acts impulsively to throw this piece of filling out of the loom when the filling is parted or cut by the usual temple thread cutter at 45 the cloth selvage.

In the drawings:—

Figure 1 is a perspective view of a portion of a filling replenishing loom having the present invention associated therewith; 50 Fig. 2 is a detached detail showing more particularly the thread catcher and its association with the thread parter and clamp; and

Fig. 3 is an enlarged detail showing a portion of the thread clamp.

The loom frame has secured thereto the bracket 1 which affords a suitable support for the shuttle feeler 2 which may be of usual construction. In the present instance the shuttle feeler 2 has a hub portion 3 through which passes the pin 4 which affords a suitable rocking support for the shuttle feeler. The shuttle feeler is normally held in its front position or toward the breast beam of the loom, and is moved 60 rearwardly to feel for the shuttle and to part and clamp the filling thread between the cloth selvage and shuttle only on call for replenishment of filling. This general construction and operation is of usual character 70 in this class of looms, and recently it has been proposed to give the shuttle feeler and the thread parting and clamping devices which are usually mounted on it, a side or lateral movement as the shuttle feeler moves 75 from its rearward feeling to its frontward or idle position, in order to prevent breakage of the filling thread which is held by the clamp and leads from the cloth selvage. In the present instance, the shuttle feeler is 80 shown as of the type wherein the lateral movement is given to the shuttle feeler, but the invention is applicable to either this type or that in which the shuttle feeler has only a movement toward and from the front of 85 the loom.

The shuttle feeler 2 has the usual diverging or beveled end portions to feel for or contact with the shuttle and to guide the filling thread into position to be cut or 90 parted by the thread-parting devices. In the present instance of the invention, the rear end portion of the shuttle feeler 2 has the upper inclined feeler end 5 and the lower inclined feeler end 6 which, as the 95 shuttle feeler moves rearwardly to feeling position, will direct the thread, as usual, into the thread-parting position. The end portions 5 and 6 of the shuttle feeler have a slot 7 between them, into which the filling thread 100 is guided to the parting devices.

Mounted on the shuttle feeler 2 is the thread parter which, in the present instance, comprises the relatively fixed cutting member 8 and the movable cutting member 105 9. These may be of usual construction and may operate in any approved manner to part the filling when the shuttle feeler and parter are in their rearward or operative position. The movable member 9 of the parter 110

is preferably mounted for rocking movement about an axis 10 on the shuttle feeler 2, and has an operating end portion 11 adapted to be engaged by the lay or a part carried thereon when the shuttle feeler and thread parter are in their rearward operative position, as usual. The particular construction of the thread parter is not of the essence of the present invention, and the character of 5 parter thus far described is one which is well known in the art. The end portion 11 of the movable parting member 9 has a pin 13 extending therefrom, which is adapted to engage an opening member 14 (Fig. 1) to open 10 the thread parter when the shuttle feeler and parter are moved toward their rearward or operative position. The opening member 14 is preferably mounted on a fixed support 15 and is connected to the support for rocking 15 movement in one direction or frontwardly, in the present instance, to permit the thread parter to pass from its rearward to its front position as the shuttle feeler moves frontwardly without opening the parter or clamps 20 and to effect opening of the parting members 8 and 9 when the shuttle feeler moves rearwardly to its operative position. These parts may all be of usual character. The support 15 in the present instance of the invention, is 25 shown as clamped at 16 to the bracket 1.

In weaving certain kinds of fabrics, for instance, such as duck or other fabrics which use a relatively heavy or strong filling thread, it is desirable that the filling thread 30 leading from the cloth selvage after the operation of the parter, may be securely clamped so that as the parter and shuttle feeler move frontwardly, the filling leading from the cloth selvage will not be pulled 35 from the clamp. The present invention therefore provides a thread clamp of novel construction and which is more especially adapted for use in weaving heavy goods, such as duck.

40 The lower member of the clamp is preferably formed as part of the lower end member 6 of the shuttle feeler, or it may be secured thereto and project laterally therefrom as indicated at 17, Fig. 1. The thread 45 engaging surface of the lower member of the clamp has a series of ribs or corrugations extending transversely thereof, which do not interfere with the proper guidance of the filling thread to the parter when the shuttle 50 feeler and parter are moved to their rearward filling engaging position.

The other member of the thread clamp 55 comprises the member 19 which is preferably coextensive with the radially-extending lower member 17 indicated in Fig. 1. The upper clamping member 19 is similarly provided with alternate ribs and corrugations 20 alternating with those of the opposed clamping member 17. The two clamping members 60 form an extended clamping surface which

projects laterally from the parts which carry them, and affords a secure clamp for holding even the heaviest character of yarn.

The upper clamping member 19 is formed on or secured to an arm which is mounted 70 on and movable with the movable thread parter. In the present instance, the arm comprises a part 21, Figs. 1 and 2, which is bolted or secured to the movable member 9 of the thread parter at 22. The arm 21 is 75 preferably formed to provide a yielding action for the clamping members 17 and 19. In the present instance the arm 21 has pivotally mounted thereon at 23, the clamp-carrying arm 24 to which the upper clamp 80 19 is secured, or with which it may be formed integral. A spring 25 normally tends to move the arm 24 toward the clamping position, but yields upwardly and is restrained from effecting movement of the arm to 85 clamping position by means of a stop 26 on the arm 21 and a coöperating stop 27 on the arm 24. The spring 25 may be appropriately secured at 28 to the arm 21 and have its end portion 29 embracing the upper portion 90 of the arm 24, the construction being such that when the thread parter 9 is moved by engagement with the lay or a part thereon after replenishing the filling, and after the shuttle feeler has been moved rearwardly to 95 feeling position, the clamping member 19 will be closed upon its coöperating clamping member 17 to securely clamp the thread leading from the cloth selvage to the filling carrier which is to be ejected; and owing to 100 the resiliency of the spring 25 the clamping action will be sufficiently yielding to provide for different thicknesses of the yarn engaged by the clamp.

Extending from the shuttle feeler 2 is a 105 supporting lug 30 carrying a laterally-extending rock shaft 31. Mounted on the rock shaft 31 is the thread catcher 32, the hub portion 33 of which may be secured to the shaft by means of a set screw 34. The 110 thread catcher 32 is provided at its free end with a hook 35 which is adapted to engage the thread leading between the cloth selvage and clamp, and to impulsively throw it from the machine under spring action. In the 115 present instance of the invention, the thread catcher 32 is under control of a spring 36 mounted upon the rock shaft 31, one end of the spring being secured to the lug 30 at 37, and the other end of the spring at 38 being 120 connected to the thread catcher, the construction being such that the spring 36 will normally tend to move the thread catcher 32 in a contraclockwise direction, and movement of the catcher responsive to the spring 125 is limited by a suitable stop such, for instance, as the pin 39 projecting from the shuttle feeler or the fixed member of the thread parter.

The rock shaft 31 has rising therefrom 130

the tensioning arm 40 which, as the shuttle 5 feeler, parter and thread catcher move from the front to rearward position after replenishment, is adapted to engage a fixed stop such as the rod 41 extending from the support 15 hereinbefore described, the construction being such that the thread catcher 32 will be rocked clockwise, or raised so that its hooked end 35 will be above the filling 10 thread *a* leading from the cloth selvage to the shuttle-box. The rod 41 is preferably connected to the support 15 adjustably as for instance, by the slotted arm 42 and the clamping nut 43, the construction being such 15 that the stop 41 may be adjusted to suit conditions of use. Similarly, the operating arm 40 may be secured to the rock shaft 31 adjustably as by means of the set screw 44, Fig. 1.

20 Normally, the shuttle feeler 2 and the parts carried thereby are maintained in their normal front position, by means usual in this class of machines, and not necessary here to describe since they form no part of 25 the present invention. When a change is called, the shuttle feeler, as usual in this class of looms, is moved rearwardly into the position substantially indicated by Fig. 1 to feel for the shuttle and ascertain if it is 30 properly boxed or within the shuttle-box. The thread parter and clamp and the thread catcher move rearwardly with the shuttle feeler, and as the thread catcher moves rearwardly, the operating arm 40 engages 35 the stop 41 and lifts or moves the thread catcher 32 in an upward direction, as indicated in Fig. 1, and against the tension of the spring 36. As the lay beats up, the filling thread leading from the cloth selvage to 40 the shuttle-box or the filling carrier to be ejected, is clamped and parted by the operation of the clamping members 19 and 17 and the parter 9, as indicated in Fig. 1. The parts are now in their rear position as indicated in Fig. 1, the thread catcher 32 being 45 positioned above the filling thread *a*. As the shuttle feeler moves forwardly after performing the above-described operations, the operating arm 40 moves away from the 50 stop 41 and the thread catcher 32 is moved to engage its hooked end portion 35 with the filling thread *a* under the impulse of the spring 36. The shuttle feeler will thus move to its forward position while the 55 filling thread *a* leading from the cloth selvage is still held by the clamps, and while the thread catcher still bears or rests upon the filling thread under the tension of the spring 36. During the subsequent operation of 60 weaving, the usual temple thread cutter will eventually part the thread at the cloth selvage, whereupon the thread catcher 32, under the action of spring 36 will have imparted to it a further lowering movement 65 and will throw the filling end leading from

the cloth selvage forwardly, out of danger of being carried into the shed.

What is claimed is:

1. In a filling replenishing loom, the combination of a shuttle feeler, a thread parter and clamp mounted on the shuttle feeler, a thread catcher mounted on the shuttle feeler to engage the filling between the cloth selvage and clamp, means for raising the thread catcher as the shuttle feeler and thread catcher move to rearward position, and means for lowering the thread catcher to engage and bear upon the filling between the cloth selvage and clamp as the shuttle feeler returns to front position and to impart a further lowering movement to the thread catcher to remove the end of the filling when it is parted at the cloth selvage.

2. In a filling replenishing loom, the combination of a shuttle feeler, a thread parter and clamp mounted on the shuttle feeler, a thread catcher having a hooked end and mounted on the shuttle feeler to engage the filling between the cloth selvage and clamp, means for raising the thread catcher as the shuttle feeler and thread catcher move to rearward position, and means for lowering the thread catcher to engage and bear upon the filling between the cloth selvage and clamp as the shuttle feeler returns to front position and to impart a further lowering movement to the thread catcher to remove the end of the filling when it is parted at the cloth selvage.

3. In a filling replenishing loom, the combination of a thread parter and clamp movable from a front to a rear position to part and clamp the filling between the cloth selvage and shuttle on call for a change of filling, a thread catcher movable with the parter and clamp and having a hooked end, means for causing the hooked end of the thread catcher to engage and rest upon the filling between the cloth selvage and parter when the parter and clamp return to front position and for giving it a further movement when the filling is parted at the cloth selvage to remove the end of filling between the parter and clamp and the cloth selvage.

4. In a filling replenishing loom, the combination of a thread parter and clamp movable to a rearward position on call for replenishment of filling to part and clamp the filling thread between the cloth selvage and shuttle, a thread catcher which is mounted for movement rearwardly with the parter and clamp and is raised as it is moved rearwardly to bear upon the filling thread between the cloth selvage and clamp as the parter and clamp return to front position, and means for causing the thread catcher to whip the engaged filling forwardly when the filling is parted at the cloth selvage.

5. In a filling replenishing loom, the com-

bination of a shuttle feeler, a thread parter and clamp, and a thread catcher mounted for movement rearwardly on call for replenishment of filling, means for causing the thread catcher to bear above the filling between the cloth selvage and thread clamp as the catcher is moved toward frontward position and to whip the filling end frontwardly when it is parted at the cloth selvage.

6. In a filling replenishing loom, the combination of a shuttle feeler, a thread parter and clamp movable with the feeler to and from a rearward position to part the filling and carry the clamped end frontwardly, a thread catcher carried by the shuttle feeler, an operating arm connected to the thread catcher, a stop which acts upon the arm to raise the thread catcher as the shuttle feeler moves rearwardly, and a spring which acts to depress the catcher and cause it to engage and bear upon the filling between the cloth selvage and clamp as the shuttle feeler moves frontwardly.

7. In a filling replenishing loom, the combination of a shuttle feeler, a thread cutter and clamp, a thread catcher mounted on the shuttle feeler and movable with it to and from a rearward position on call for replenishment of filling, a spring connected to the thread catcher, means for lifting the thread catcher above the thread between the thread clamp and cloth selvage as the shuttle feeler is moved rearwardly on call for replenishment of filling and permitting the thread catcher to engage and bear upon the thread in response to the spring when the shuttle feeler is moved to its front position and to further move the thread catcher when

the thread is parted at the cloth selvage for removing the thread.

8. In a loom, the combination of a shuttle feeler, a thread parter and clamp mounted on the shuttle feeler, a thread catcher mounted on the shuttle feeler, means for causing the shuttle feeler with the thread parter and clamp and thread catcher to be moved rearwardly on call for replenishment of filling, means for lifting the thread catcher to a position above the filling as it is moved rearwardly with the shuttle feeler, and means for depressing the thread catcher to engage above the filling as the shuttle feeler and thread catcher move frontwardly and to thereafter whip the filling frontwardly from between the cloth selvage and the parter and clamp.

9. In a filling replenishing loom, the combination of a shuttle feeler, a thread parter and clamp, a thread catcher mounted on the shuttle feeler, a spring normally acting to swing the thread catcher in a downward direction, a stop which causes the thread catcher to be raised into position above the thread between the parter and clamp and the cloth selvage as the shuttle feeler is moved to its rearward position on call for replenishment of filling and to rest upon and be supported by the thread between the parter and clamp and the cloth selvage as the shuttle feeler is returned to front position, and a second stop to limit the further downward movement of the thread catcher when the thread is parted at the cloth selvage.

In testimony whereof I have signed my name to this specification.

MELVIN L. STONE.
